ADHESIVE TAPE DISPENSER OR THE LIKE

Tatsuo Kikuchi and Takashi Toyama, Tokyo, Japan, assignors to Nichiban Co., Ltd., Tokyo, Japan

Filed July 30, 1971, Ser. No. 167,885

Term of patent 14 years

Int. Cl. D19—02

U.S. Cl. D74—1 B

FIG. 1

FIG. 6

FIG. 5

FIG. 3

FIG. 4

FIG. 7

FIG. 8

FIG. 1 is a front elevation of an adhesive tape dispenser or the like showing our new design;

FIG. 2 is a rear elevation of the adhesive tape dispenser shown in FIG. 1;

FIG. 3 is a top plan view thereof;

FIG. 4 is a bottom plan view thereof;

FIG. 5 is a right side elevation thereof;

FIG. 6 is a side elevation showing the opposite side thereof;

FIG. 7 is a section along the lines VII—VII of FIG. 1; and

FIG. 8 is a perspective front view thereof.

We claim:

The ornamental design for an adhesive tape dispenser or the like, as shown.
